United States Patent Office.

JOHN CARROLL, OF NEW YORK, N. Y.

Letters Patent No. 65,172, dated May 28, 1867.

IMPROVED BATH-TUB.

The Schedule referred to in these Letters Patent and making part of the same.

TO ALL WHOM IT MAY CONCERN:

Be it known that I, JOHN CARROLL, of the city, county, and State of New York, have invented a new and improved Bath-Tub; and I do hereby declare that the following is a full, clear, and exact description thereof, which will enable others skilled in the art to make and use the same, reference being had to the accompanying drawings forming part of this specification, in which—

Figure 1 represents a vertical cross-section of my improved bath-tub.

Figure 2 is a longitudinal vertical section of the same.

Similar letters of reference indicate corresponding parts.

The object of this invention is to construct a bath-tub of sheet metal and wood, in such a manner that it will be durable, light, and easily packed for transportation.

The bath-tubs now generally made of sheet metal and wood, are made square on the outside, the bottom of the metal being almost flat. The wood-work was thick and heavy, and when these tubs were to be packed for transportation they would occupy a very large room. I have overcome these difficulties by making the bottom of the sheet metal half circular, or nearly so. The head and foot-rest can then be easily soldered to the main part, using double seam joints for the purpose. I then cover the outside of the tub with a layer of very thin wood, which is made either in one or more pieces, and which conforms completely to the shape of the metal; so that the outside of the tub is also half circular. The tubs can in this shape be set together, one within the other, so that when packed for transportation twelve (12) of these tubs will occupy no more room than two of the common ones. Provision is made for carrying off the overflowing and waste-water.

A represents a tub, made of sheet metal, of any suitable description, and provided with a half circular, or nearly so, bottom, as shown in fig. 1. It is made of three (3) pieces, *a*, *b*, and *c*; *a* being the head-rest, *b* the foot-rest, and *c* the body of the tub. The three pieces are double seamed, and then soldered together in any suitable way, being formed on a block of suitable shape. *B* is a layer of thin wood, laid around *A*, as shown, so that the shape of the outside of the tub is like that of the inside. The wood may be as thin as a veneer, and is cut or shaved from any suitable kind of tree. The part enclosing the body *c* may be made of one or more pieces, as well as that which encloses *a*. The joints are glued together, or otherwise made secure and water-tight. Outside of the vertical foot-rest *b* is arranged a board, *C*, which is heavier than the rest of the wooden casing. *d* is a hole in the upper part of the foot-rest *b* for the purpose of carrying off the water when the same rises too high in the tub. The board *C* is provided with a groove, *e*, which connects the hole *d* with the waste pipe *f*, which is arranged at the bottom of the pan, as shown in fig. 2. The upper edge of this tub is or may be strengthened by a lining, *g*, of sheet metal, or any other suitable material, as shown in the drawings. Supports *D* may be arranged at the bottom of the tub when the same is to be set up. For packing, the same should not be on the tub, and the same will then be enabled to be set one into another, as is indicated by red lines in fig. 2. The tub may be strengthened by laying metal or wooden bands around the wood-work at suitable distances; but when required, they may be omitted.

I claim as new, and desire to secure by Letters Patent—

1. The bath-tub, consisting of the body *c*, with a half circular bottom, head-rest *a*, and foot-rest *b*, all composed of sheet metal, and surrounded by a layer, *B*, of thin wood, in such a manner as to conform to the shape of the inside of the tub, the wooden foot-board *C*, adjustable support *D*, and metallic lining *g*, substantially as herein shown and described.

2. The thin covering *B* of wood, when laid around the body of a bath-tub, with semicircular bottom, substantially as and for the purpose herein shown and described.

JOHN CARROLL.
